DESIGN FOR A COAT

Jack Schumer, New York, N. Y.

Application July 6, 1938, Serial No. 78,304

Term of patent 3½ years

To all whom it may concern:

Be it known that I, Jack Schumer, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein,

The characteristic feature of my design resides in the specific raglan sleeves in combination with the coat as shown.

I claim:

The ornamental design for a coat, substantially as shown, and described.

JACK SCHUMER.
